UNITED STATES PATENT OFFICE.

CHARLES FRANKLIN ALT, OF WARREN, PENNSYLVANIA.

CULVERT.

No. 918,723.

Specification of Letters Patent. Patented April 20, 1909.

Application filed August 13, 1908. Serial No. 448,399.

To all whom it may concern:

Be it known that I, CHARLES F. ALT, a citizen of the United States, residing at Warren, in the county of Warren and State 5 of Pennsylvania, have invented certain new and useful Improvements in Culverts, of which the following is a specification, reference being had to the accompanying drawings.

This invention relates to improvements in 10 metal culverts for use beneath roadways and for analogous purposes.

The object of the invention is to provide a galvanized metal culvert which will be simple, strong and durable in construction, 15 comparatively inexpensive to produce and to construct and exceedingly durable and effective in use.

With the above and other objects in view, the invention consists of the novel features 20 of construction and the combination and arrangement of parts hereinafter fully described and claimed, and illustrated in the accompanying drawings, in which—

Figure 1 is a vertical cross section through 25 a culvert constructed in accordance with the invention; Fig. 2 is a view partly in side elevation and partly in vertical section taken on the plane indicated by the line 2—2 in Fig. 1; and Fig. 3 is a detail transverse section through a slightly modified form of the invention.

The improved culvert is formed from a plurality of arch-shaped body sections 1 of corrugated galvanized metal arranged with 35 their adjacent ends overlapping and with their side edges resting upon flat metal stringers 2. The body sections 1 are substantially semi-circular shaped in cross section and they are formed with transverse 40 corrugations 3 which effectively strengthen them. The endmost corrugation of each section overlaps the corresponding corrugation of the next adjacent section, as shown at 4, but in order to more effectively reinforce 45 the joint one or more metal straps 4^a may be secured by bolts, rivets or similar fastenings 4^b to the top or exterior surfaces of said ends of the sections, as clearly shown in Fig. 2. The connecting or joint plate 4^a is shaped to 50 fit the two body sections and overlaps the joint or seam, thereby greatly strengthening the latter. The edges of the body sections 1 are effectively secured to the base formed by the stringers 2, by means of suitable clips 55 and bolts, rivets or similar fastenings. Said clips are here shown in the form of angle

metal plates 5 arranged in staggered relation on both the inner and outer faces of the sections and secured to the latter and also to the stringers by bolts 6. Instead of the 60 angle clips or plates 5 I may employ angle metal bars to unite the body sections to the stringers. These angle metal bars would extend continuously from end to end of the culvert and would greatly strengthen and 65 reinforce the same. The stringers extend longitudinally throughout the length of the culvert and their abutting ends are united by a joint plate 7 arranged beneath them and secured by certain of the bolts 6, as 70 clearly shown in Fig. 2.

The stringers 2 may be merely flat plates, as shown in Fig. 3, so that the bottom of the culvert will be formed by the earth upon or within which it is located, but they are preferably made of angular shape in cross section, as shown in Fig. 1, so that the edges of the body sections may be secured to their horizontal portions or flanges 8 and their inwardly or downwardly projecting flanges 9 80 may be secured by bolts or similar fastenings 10 to metal bottom sections 11. These stringer sections may be flat or curved transversely, as shown in Fig. 1, and they may also be either plain or corrugated. The fastening bolts 10 pass through the bottom sections 11 and the flanges 9 of the stringers but it will be understood that clips or other fastening means may be substituted and that any other fastening means other than the 90 angle plates 5 may be employed for uniting the corrugated body sections to the stringers or base.

From the foregoing it will be seen that the invention provides an exceedingly simple 95 culvert, the parts of which may be produced at a small cost and quickly and easily put together. It will be further noted that it will be exceedingly strong, rigid and durable. It will also be seen that owing to the shape 100 of the several parts of the culvert it may be shipped to the point where it is to be used in knocked down condition with its parts nested or bundled and bolted together.

Having thus described the invention what 105 is claimed is:

1. A metal culvert comprising metal stringers, arch-shaped body sections having their edges resting upon said stringers and right angular metal clips arranged upon both 110 the inner and outer faces of said body sections and each having one member secured

to one of said body sections and its other member secured to one of said stringers.

2. A metal culvert comprising stringers, arch-shaped body sections corrugated transversely and having their ends overlapping and their edges resting upon said stringers, and angle metal clips uniting said sections to the stringers.

3. A metal culvert comprising metal stringers, arch-shaped body sections having their edges resting upon said stringers and fastening means uniting said sections to the stringers.

4. A metal culvert comprising metal stringers, arch-shaped body sections corrugated transversely and having their edges resting upon said stringers and their ends overlapping, and angle metal plates uniting the body sections to the stringers and arranged upon both the inner and outer faces of said body sections.

5. A metal culvert comprising stringers, arch-shaped body sections having their edges

secured to said stringers, and metal bottom sections between said stringers.

6. A metal culvert comprising stringers of angular shape in cross section, arch-shaped body sections secured to the horizontal flanges of said stringers and curved bottom sections secured to the depending flanges of said stringers.

7. A metal culvert comprising metal stringers, arch-shaped body sections corrugated transversely and having their ends overlapping and their edges resting upon the stringers, joint plates extending over the joints and united to the overlapping sections and fastenings uniting the body sections to the stringers.

In testimony whereof I hereunto affix my signature in the presence of two witnesses.

CHARLES FRANKLIN ALT.
